UNITED STATES PATENT OFFICE.

PATRICK W. CORCORAN, OF SENECA, ILLINOIS.

HARNESS-SADDLE.

SPECIFICATION forming part of Letters Patent No. 337,047, dated March 2, 1886.

Application filed December 29, 1885. Serial No. 186,971. (No model.)

To all whom it may concern:

Be it known that I, PATRICK W. CORCORAN, a citizen of the United States, residing at Sene-
5 ca, in the county of La Salle and State of Illi-
nois, have invented certain new and useful
Improvements in Harness-Saddles; and I do
declare the following to be a full, clear, and
exact description of the invention, such as will
enable others skilled in the art to which it ap-
10 pertains to make and use the same, reference
being had to the accompanying drawings, and
to the letters and figures of reference marked
thereon, which form a part of this specifica-
tion.

15 The invention relates, generally, to the check-
hooks which are used upon the saddles of
harness, and specially to particular means
whereby said hooks may be made to slide
20 back and forth on the saddle, so as to loosen
or tighten the check-rein, as hereinafter de-
scribed.

25 Figure 1 of the drawings is a top or plan
view of a harness-saddle provided with my
invention. Figs. 2 and 3 are longitudinal
vertical sections, one showing the slide locked
20 to the saddle, while the other shows it loose
and resting thereon. Fig. 4 is a perspective
view of the guide-piece.

30 In the drawings, A represents an ordinary
harness-saddle, to the top of which, and in-
front thereof, I make fast the guide-piece B,
which has vertical parallel sides b b and a
35 rear edge, b^3 . In this guide-piece works a
slide, C, provided with the rear hook, c , cross-
slot c' , and front flange, c^2 . On the front end
of this slide is fastened the check-hook D by
a screw, d , or otherwise. The guide-piece B
40 is attached by a screw, b' , and nut b^2 to the
saddle A, while it carries on its top a fast
rearwardly-extending spring, E, which bears
upon the rear end of the slide C.

45 F is a front pin held forward by a spring,
both working in a cavity of the guide-piece B,
and against the downwardly-projecting flange
 c^2 of the slide-piece C.

G is a strap passing through the cross-slot
near the rear end of slide C, there fastened,
and passing back within reach of the driver.

The operation is as follows: As shown in
Fig. 2 of the drawings, the slide-hook c is 50
caught on the edge b^3 of the guide-piece B, so
that the horse's head, is checked up in the
usual manner. When it is wished to uncheck
the horse's head for any reason whatever, the
55 driver simply pulls the strap G, and at the
same time raises it up, so as not only to dis-
connect hook c from the edge b^3 , but to lift said
hook against the spring E, so that it may pass
over the saddle. As soon as he relaxes his
60 pull, but still holds up the strap, the spring-
pin F, pushing against the flange, draws the
slide, with its hook, over the saddle. The
horse may then draw it as far over the saddle
as the strap—in hand or fastened to dash-board
65 of vehicle—will permit. When, again, the
driver wishes to check up, he simply pulls
back the slide C until the hook c is in rear of
the point b^3 , and drops it, when the super-
posed spring E will at once force down the
70 hook, and the spring-pin F will compel it to
catch on the point or edge b^3 .

Having thus described all that is necessary
to a full understanding of my invention, what
I claim as new, and desire to protect by Let-
ters Patent, is—

75 1. A check-hook slide having the rear hook,
 c , combined with a guide-piece, B, having side
flanges, b b , made fast to the saddle, and having
the rear edge, b^3 , as and for the purpose set
forth.

80 2. The superposed spring E, combined with
the slide C and guide-piece B, provided, re-
spectively, with the hook c and edge b^3 , as and
for the purpose set forth.

85 3. The combination, with a harness-saddle,
of the fixed guide-piece B, having sides b b
and rear edge, b^3 , the slide C, having hook c ,
slot c' , and front flange, c^2 , the spring E, and
the spring-pin F, whereby the check-hook
90 may be used in the manner described.

In testimony whereof I affix my signature in
presence of two witnesses.

PATRICK W. CORCORAN.
